JAN 30, 1883

UNITED STATES PATENT OFFICE.

GEORGE F. EBERHARD, OF CLEVELAND, OHIO.

DESIGN FOR A HARNESS-BIT.

SPECIFICATION forming part of Design No. 13,547, dated January 30, 1883.

Application filed November 11, 1882. Term of patent 14 years.

To all whom it may concern:

Be it known that I, GEORGE F. EBERHARD, of Cleveland, in the county of Cuyahoga and State of Ohio, have invented and produced a new and original Design for Harness-Bits, of which the following is a specification, reference being had to the accompanying photograph, making a part thereof.

My invention relates to a new design for harness-bits; and it consists particularly in the contour and ornamentation of the cheek-piece, which will be hereinafter more particularly described and claimed.

In the accompanying photographic illustrations, Figure 1 shows what is known as a "half-cheek" bit, and Fig. 2 what is understood to be a "full-cheek" bit—that is to say, a bit with cheek-pieces projecting from both sides of the mouth-piece or bit.

20 In both views like letters of reference indicate like parts.

A is the mouth-piece or bit, B B the reins, and C C the cheek bars or pieces. The cheeks and rings are cast integral. The frame-like cheek C is tapering in form, and is smallest where it joins the ring. The appearance of this frame is highly improved by the ornamental bar-work at *n* and *o*, and the foliated figure at *m*. The bars *n* and *o* cross one another at about the middle of the frame, the two bars *o o*, running longitudinally of the frame, being straight, while the transversely-disposed bar *n*

is curved and concentric with the divided end bar, *e*, of the cheek-piece. The trifoliated ornament *m* connects the ends of the two long bars *o o*, which break through and divide the end bar, *e*.

My design of cheek-piece may of course be used in either a half-cheek or a full-cheek bit, and in either a snaffle or bar bit, and I therefore consider my invention unlimited as to any particular kind of bit.

What I claim as novel, and desire to secure by Design Letters Patent, is—

1. A harness-bit having the rings and cheek-pieces of substantially the design shown and described.

2. In a harness-bit, the cheek-pieces made in design substantially as shown and described.

3. In a harness-bit, the cheek-pieces made frame-like and tapering in form, and provided with ornamentation, substantially as shown and described.

4. A cheek-piece for a harness-bit, having ornamentation composed of bar-work *n* and *o*, disposed as shown.

In witness whereof I have hereunto set my hand this 3d day of November, 1882.

GEORGE F. EBERHARD.

In presence of—

ALFRED A. POPE,
WALTER A. BIDDLE.
